UNITED STATES PATENT OFFICE.

CLARENCE L. BROWN, OF CLEVELAND, OHIO.

TEMPERATURE-RECORDING DEVICE.

1,115,496.

Specification of Letters Patent.

Patented Nov. 3, 1914.

Application filed June 21, 1912. Serial No. 705,035.

To all whom it may concern:

Be it known that I, CLARENCE L. BROWN, a citizen of the United States, residing at Cleveland, in the county of Cuyahoga and State of Ohio, have invented certain new and useful Improvements in Temperature-Recording Devices, of which the following is a specification.

This invention relates to improvements in temperature recording devices and is designed especially for recording the temperatures during the process of pasteurization of milk, grape juice, beer and other liquids.

The principal object of the invention is to provide an instrument which may be connected to an individual receptacle or bottle containing the liquid to be pasteurized and will record the varying temperatures of same as said receptacle passes through the pasteurizing machine.

Another object of the invention is to provide an instrument of the above class of simple compact construction, in which a revolving cylinder carries a chart for receiving the record.

With the above and other objects in view as will be understood, the invention consists in certain combinations and arrangements of the parts hereinafter fully described in connection with the accompanying drawings illustrating a preferred embodiment thereof, and the novel features of the invention will be distinctly pointed out in the appended claims.

35 In the drawings like characters of reference indicate corresponding parts.

Figure 1 is a sectional elevation of a device constructed in accordance with my invention, Fig. 2 illustrates the chart used in connection with the device, Fig. 3 is a cross sectional view taken on line 3—3 of Fig. 1, Fig. 4 is a similar view taken on line 4—4 of Fig. 1, and Fig. 5 is an enlarged perspective view showing the pencil or marker held in the marking arm.

Referring to the drawings, 1 represents a bottle containing a liquid 2 to be pasteurized by passing the bottle through a pasteurizing machine in the ordinary manner.

50 The invention consists of a suitable air and water tight casing for inclosing the operative parts, which is preferably constructed of an annular base flange 3 and a corresponding dome flange 4, each of which

are oppositely grooved as indicated at 5 55 and 6 for receiving the lower and upper edges respectively of a transparent glass cylinder 7. The base flange 3 of the casing may be connected to the neck of the bottle 1 in any suitable manner, as for instance by 60 providing the same with a depending ring flange 8 which is adapted to receive a suitable rubber washer 9 forced onto the open end of the bottle. Projecting upwardly from the base flange 3 are a plurality of supports 10, preferably arranged in a triangular formation, and to the upper end of these supports is secured by means of screws 11 a cupped horizontal annular flange 12. The outer periphery of the flange 12 is reduced 65 at 13 to provide a bearing and also a shoulder 14 for rotatably supporting a vertically arranged cylinder 15, which carries on its outer face a chart 16, on which are recorded the temperatures as hereinafter described. 70

The cylinder 15 is rotated at a suitable uniform speed by the following mechanism. The upper end of said cylinder is provided with an inwardly extending annular rim 17 having teeth 18 on its edge, and said teeth 80 are engaged by a pinion 19 driven by a spring motor represented by 20, or other suitable means, which is securely fixed to a central post 21 projecting upwardly from the base of the cupped flange 12. 85

The chart 16 preferably consists of a strip of paper of a width corresponding to the height of the cylinder 15, and of sufficient length to encircle the cylinder with one end slightly overlapping the other. One end 90 of the chart is provided with vertically spaced holes 22 for fitting over the projecting ends of correspondingly arranged pins 23 which are fixed in the cylinder, and the other end with similar holes 24 for engaging said pins after the chart has been wrapped around the cylinder to hold it in normal position. The chart is divided longitudinally by equally spaced vertical time lines 25 which are preferably marked as 100 shown at 26 to represent periods of ten minutes up to an hour. Any desired number of hours may be represented on the chart. The chart is also divided transversely by equally spaced degree or temperature lines 27 preferably marked as at 28 from 10 degrees to 60 degrees. The record line, indicating the varying temperatures at 105

which the liquid contained in the bottle 1 is being pasteurized, is traced on said revolving chart by a marker or pencil 29 which is actuated relatively to the temperature of 5 the liquid as follows. The pencil 29 is held in the bifurcated end 30 of a vertical arm 31, which is pivoted at 32 to the free forked end of a horizontal lever 33 pivotally supported at its other end on a pin 34 carried 10 by a pair of bearing lugs 35 projecting from the base flange 3. The horizontal lever 33 is held in normal position by means of a coiled balance spring 36, which depends from the cupped flange 12, and said arm 31 is held in normal position to keep the pencil 29 in contact with the chart 16, by means of 15 a coiled spring 37 which connects the arm to said lever.

The horizontal lever 33 is moved upwardly 20 on its pivot pin 34 to actuate the pencil 29 vertically according to the temperature of the liquid 2 in the bottle 1, by means of a plunger 38 which is pivoted to said lever at 39 and depends into the upper portion of a 25 tubular extension 40 depending from the base flange 3 into said bottle. The tubular extension 40 is enlarged at its free lower end to form a bulb 41 and contains a suitable substance 42 such as mercury, that will contract and expand relatively with the temperature of the liquid 2 in said bottle and thereby force the plunger 38 upwardly or allow it to descend.

The operation of the device follows: Assuming that the instrument is attached to a bottle as shown in Fig. 1, and the bottle containing liquid at a normal temperature is passed through a pasteurizing machine. The chart illustrated in Fig. 2 having been 40 fixed to the cylinder 15, the pencil 29 being in contact with the chart at the intersection of its lowest horizontal temperature line and one of the zero vertical time lines, and the cylinder rotated by the spring motor so 45 that the chart will travel from said zero time line to the next zero time line in sixty minutes. As the liquid in the bottle becomes heated during pasteurization, the mercury in the bulb of the tubular extension expands, and rising in the tubular extension forces the plunger 38 upwardly. As the temperature of the liquid in the bottle becomes cooler, the mercury relatively contracts, thereby allowing the plunger to descend. 50 Said expansion and contraction causes the pencil to move vertically, and as the chart is traveling longitudinally, a line will be traced on said chart showing the temperature at which the liquid was pasteurized at any particular division of time on the chart. In this way an accurate record of the varying pasteurizing temperatures is automatically obtained.

It is to be understood, that slight changes 60 in the details of construction and arrange-

ment of the parts may be made within the scope of the claims, without departing from the spirit of the invention.

Having fully described my invention what I claim is:

1. In a temperature recording device, the combination of a casing, a cylinder rotatably mounted in the casing, means for rotating the cylinder, a chart carried on the periphery of the cylinder, a tubular extension communicating with the interior of the casing, a substance in the tubular extension readily expanded and contracted by heat and cold, an upright arm, a pencil supported by the arm in contact with the chart, a lever pivotally supported in said casing and pivoted to the arm, a spring connecting said arm to said lever for holding said pencil in contact with said chart, and a plunger slidably mounted in the tubular extension for actuating said lever to cause the pencil to move in a straight line at a right angle to the travel of the chart relatively to the expansion and contraction of the substance in said tubular extension, substantially as described. 70 75 80 85 90

2. In a temperature recording device, the combination of a casing, a flange fixed within the casing, a vertical cylinder rotatably mounted on the flange, means for rotating the cylinder, a chart, means for removably fixing the chart to the periphery of the cylinder, a tubular extension depending from the casing, mercury in the tubular extension, a horizontal lever pivotally supported at one end within the casing, an upright arm pivoted to the free end of the lever, a pencil carried by the arm, a spring connecting said arm to said lever to hold the pencil in contact with said chart, and a plunger pivoted to said lever near its pivoted end and slidably mounted in said tubular extension to cause said pencil to move in a straight line at a right angle to the travel of the chart relatively to the expansion and contraction of the mercury in said tubular extension, substantially as described. 95 100 105 110

3. In a temperature recording device, the combination of a casing, a flange fixed within the casing, a vertical cylinder rotatably mounted on the flange, means for rotating the cylinder, a chart, means for removably fixing the chart to the periphery of the cylinder, a tubular extension depending from the casing, mercury in the tubular extension, means for attaching the casing to a receptacle containing liquid to be pasteurized so that the tubular extension projects into the liquid, a horizontal lever pivotally supported at one end within the casing below said flange, an upright arm pivoted to the free end of the lever, a pencil carried by the arm, a spring connecting said arm to said lever to hold the pencil in contact with said chart, a spring connecting the shor- 115 120 125 130

zontal lever to said flange to keep the lever in normal balanced position, and a plunger pivoted to said lever and slidably mounted in said tubular extension to be actuated by the expansion and contraction of the mercury to move the pencil vertically in a straight line, substantially as described.

In testimony whereof I affix my signature in presence of two witnesses.

CLARENCE L. BROWN.
